US0D1000212S

(12) **United States Design Patent** (10) **Patent No.:** **US D1,000,212 S**
(45) **Date of Patent:** **** Oct. 3, 2023**

(54) **MUG**

- (71) Applicant: **Lifetime Brands, Inc.**, Garden City, NY (US)
- (72) Inventor: **Clay Allen Burns**, New York, NY (US)
- (73) Assignee: **LIFETIME BRANDS, INC.**, Garden City, NY (US)
- (**) Term: **15 Years**
- (21) Appl. No.: **29/748,119**
- (22) Filed: **Aug. 27, 2020**
- (51) LOC (14) Cl. **07-01**
- (52) U.S. Cl. **USPC D7/536; D7/533**
- (58) **Field of Classification Search**
USPC D7/300.1, 507, 509, 510, 529, 531, 533, D7/536, 537, 538, 543, 60, 2, 608; D9/503, 716
CPC A47J 31/02; A47J 31/14; A47G 19/16; A47G 19/14; A47G 19/2227; A47G 19/2205

(57) **CLAIM**

The ornamental design for a mug, as shown and described.

DESCRIPTION

FIG. 1 is a top perspective view of the first embodiment of a mug.

FIG. 2 is a front elevation view of the mug of FIG. 1.

FIG. 3 is a rear elevation view of the mug of FIG. 1.

FIG. 4 is a left side elevation view of the mug of FIG. 1.

FIG. 5 is right side elevation view of the mug of FIG. 1.

FIG. 6 is a top plan view of the mug of FIG. 1.

FIG. 7 is a bottom plan view of the mug of FIG. 1.

FIG. 8 is a top perspective view of another embodiment of a mug.

FIG. 9 is a front elevation view of the mug of FIG. 8.

FIG. 10 is a rear elevation view of the mug of FIG. 8.

FIG. 11 is a left side elevation view of the mug of FIG. 8.

FIG. 12 is right side elevation view of the mug of FIG. 8.

FIG. 13 is a top plan view of the mug of FIG. 8; and,

FIG. 14 is a bottom plan view of the mug of FIG. 8.

The evenly dashed broken lines in the figures illustrate portions of the mug that form no part of the claimed design. The dash-dot-dash broken lines in the figures show boundaries of the claimed design and form no part of the claimed design.

1 Claim, 14 Drawing Sheets
